Attorney

UNITED STATES PATENT OFFICE.

GEORGE GREER HATFIELD, OF JENKINS, KENTUCKY, ASSIGNOR OF ONE-THIRD TO
JOHN DELANEY, OF MOUNT SAVAGE, MARYLAND.

OILING DEVICE.

Application filed July 28, 1924. Serial No. 728,755.

This invention relates to oiling devices, and more particularly to flange oilers for the wheels of locomotives.

An object of the invention is to provide means for regulating the oil feed of a flange oiler.

Heretofore, flanges of locomotive wheels have been oiled from a receptacle by a gravity feed and the feed pipe has been provided with a valve to regulate the flow of oil. The small quantity of oil necessary for this purpose necessitates the use of a valve having such a small opening that any foreign matter in the oil clogs the feed pipe. If a larger quantity of oil is fed, it not only results in waste, but also permits some oil to settle on the tread of the wheel, which causes slipping.

In the present invention, I provide an intermittent feed, whereby the valve may be provided with an opening sufficiently large to prevent the valve or the feed pipe from becoming clogged by dirt or foreign matter and at the same time, permit proper regulation of the oil feed.

A further object of the invention is the provision of an attachment adapted to be arranged in the end of the feed pipe and contact with the flange of the wheel to deliver the oil thereto.

In the accompanying drawings, I have shown one embodiment of the invention. In this showing:

Figure 1 is a side elevation of a portion of the truck of a locomotive, showing the invention applied,

Figure 2 is a vertical sectional view through the oil receptacle,

Figure 3 is a sectional view of the lower end of the feed pipe.

Figure 4 is a sectional view of the intermittent feed mechanism,

Figure 5 is a detail sectional view on line 5-5 of Figure 4, and,

Figure 6 is a rear elevation of the contact member arranged in the feed pipe.

Referring to the drawings, the reference numeral 1 designates the wheels of a locomotive adapted to travel on a track 1'. The flange oiler consists of a receptacle 2, adapted to be supported in any suitable manner on the locomotive frame, adjacent the wheels to be oiled. The receptacle is provided with

a feed opening 3, adapted to receive the end of a pipe 4, connected to an oil reservoir 5 from which the oil is fed by gravity to the receptacle 2. The bottom of the receptacle is provided with an outlet opening 6, adapted to receive a pipe 7, by means of which the oil is conveyed to the wheels. As shown, the pipe 7 is connected to a horizontal pipe 8, extending between the two wheels of a truck, and a substantially Y-shaped member 9 is arranged on each end of this pipe. A rod 10 is arranged in the Y-shaped connection and this rod is provided with a flat face 11, adapted to contact with the flange 12 of the wheel to deliver oil thereto.

Suitable means are provided for intermittently feeding oil from the receptacle 2 to the pipe 7. As shown, the receptacle is provided with a cover 13, having a peripheral flange 14. This flange is internally threaded and adapted to engage external threads on the top of the receptacle. A boss 15 is arranged in the center of the cap or cover and is adapted to form a bearing for a shaft 16. The opposite end of the shaft is journaled in the bottom of the cup. A disk 17 is arranged in the bottom of the cup and keyed to the shaft by means of a key 18. This disk is provided with one or more openings 19. A second disk 20 is arranged above the first mentioned disk. The interior wall of the receptacle is provided with a groove 21, adapted to receive a key 22, which also engages a groove in the upper disk to prevent movement thereof. The upper disk is provided with an opening 23, arranged concentric with the opening or openings 19. A spring 24 is arranged within the receptacle and engages the disks to retain them in proper position.

The upper end of the shaft 16 is provided with a ratchet wheel 25. As shown, this wheel is provided with upper and lower flanges 26. A skeleton member 27, in the form of a rectangle, is arranged between the guides 26 and the opposite sides of this member are provided with ratchet teeth 28, extending in opposite directions. One end of the member 27 is provided with an arm 29, which is connected to a lever 30, as at 31. The lever is pivotally mounted on a suitable part of the locomotive and the opposite end thereof is provided with an eye, adapted to

receive the locomotive valve rod 33. As shown, collars 34 are arranged on opposite sides of the lever 30.

In operation, the normal movement of the valve rod when the locomotive is running, swings the lever 30 on its pivot. This causes the skeleton frame 27 to reciprocate and as it moves in one direction, one set of ratchet teeth engage the teeth 25 to reciprocate the shaft 16 through a portion of a revolution. As the shaft revolves in the opposite direction, the other set of teeth 28 engage the teeth 25 to continue the reciprocation of the shaft. The movement of the shaft causes the lower disk 17 to intermittently revolve, which causes the opening or openings 19 to be brought into alignment with the opening 23. As the opening 19 comes into alignment with the opening 23, a quantity of oil sufficient to fill the opening 19 is delivered from the receptacle and this quantity of oil is carried around in the opening 19 until it comes in alignment with the outlet opening 6. The oil is then delivered through the pipes 7 and 8 and feeds down the rods 10 to the flange 12 of the wheel. The rods 10 are free to move in the Y-shaped connections 9, which permits them to remain in contact with the flange of the wheel at all times and the flattened face 11 facilitates the delivery of oil to the flange.

It will be apparent that the quantity of oil delivered can be regulated by changing the size of the opening 19 in the lower disk or by increasing or decreasing the number of such openings.

It is to be understood that the form of my invention herewith shown and described is to be taken as a preferred example of the same, and that various changes in the shape, size, and arrangement of parts may be re-

sorted to without departing from the spirit of the invention or the scope of the subjoined claims.

I claim:

1. A flange oiler comprising a pipe arranged horizontally between a pair of adjacent locomotive wheels and having its ends arranged in proximity to said wheels to deliver lubricant thereto, and means for supplying lubricant to said pipe, said means being arranged above and intermediate the ends of said pipe and including a shaft, and connections between said shaft and a moving part of the locomotive for intermittently supplying lubricant to said pipe. 45

2. A flange oiler comprising a pipe arranged between a pair of adjacent locomotive wheels and having its ends arranged in proximity to said wheels to deliver lubricant thereto, and means for supplying lubricant to said pipe, said means being arranged above and adjacent said pipe and including a vertical rotatable shaft, a horizontal ratchet wheel carried by said shaft, 60 a pair of oppositely arranged rows of ratchet teeth disposed adjacent said ratchet wheel, and connections between said rows of teeth and a moving part of the locomotive for actuating said rows of teeth. 65

3. A device constructed in accordance with claim 2 provided with a frame to which said rows of teeth are connected, the connections between said rows of teeth and the moving part of the vehicle being adapted to 70 reciprocate said rows of teeth in a line coincident with the plane of said ratchet wheel, said rows of teeth being arranged parallel to each other in lines at an angle to the line of reciprocation of said teeth. 75

In testimony whereof, I affix my signature.

GEORGE GREER HATFIELD. 80
